Primary Examiner — Katrina A Betton(74) *Attorney, Agent, or Firm* — Suzanne Kikel, Patent Agent(57) **CLAIM**

The ornamental design for a trailer for hauling logs, as shown and described.

DESCRIPTION

FIG. 1 is a front perspective view of a trailer for hauling logs, showing my new design;

FIG. 2 is a front elevation view thereof;

FIG. 3 is a rear elevation view thereof; left side elevation view thereof;

FIG. 4 is a left side elevation view thereof;

FIG. 5 is a right-side elevation view thereof;

FIG. 6 is a top plan view thereof; and,

FIG. 7 is a bottom plan view thereof.

The broken lines showing in FIG. 1 of a log is for illustrative purposes only and forms no part of the claimed design.
